UNITED STATES PATENT OFFICE.

WALTER J. BARRON, OF BROOKLYN, NEW YORK, ASSIGNOR TO THE DENSMORE TYPEWRITER COMPANY, OF SYRACUSE, NEW YORK, A CORPORATION OF NEW YORK.

TYPE-WRITING MACHINE.

SPECIFICATION forming part of Letters Patent No. 687,000, dated November 19, 1901.

Application filed April 4, 1898. Serial No. 676,372. (No model.)

To all whom it may concern:

Be it known that I, WALTER J. BARRON, a citizen of the United States, and a resident of the borough of Brooklyn, county of Kings, 5 and city and State of New York, have invented certain new and useful Improvements in Type-Writing Machines, of which the following is a specification.

The main object of my invention is to provide a cylindrical platen with a simple and effective card holder or clamp; and to this end it consists, primarily, in combining with the platen shaft or axle a card-holding clamp or device which is adapted to be raised or projected by a movement of said shaft or axle to enable the insertion or introduction of the leading edge of a card or stiff piece of paper and to then clamp or firmly hold the same upon the platen to insure its proper feed therewith in line-space direction, and, secondarily, in certain other features of detail construction and arrangement, all as will be hereinafter more fully described, and particularly pointed out in the appended claims.

In the accompanying drawings, Figure 1 represents a portion of the carriage of a "Densmore" type-writing machine and a central vertical section through the platen, which is provided with my improved card-holder. Fig. 2 is a vertical cross-section thereof taken at the line $x x$ of Fig. 1. Fig. 3 is an end view of the platen detached and looking at the right-hand end thereof. Fig. 4 is a vertical section taken at the line $u u$ of Fig. 1. Fig. 5 is a partial central vertical longitudinal section through a platen and showing a card-holder of different detail construction. Fig. 6 is a vertical cross-section taken at the line $z z$ of Fig. 5. Fig. 7 is a view similar to Fig. 5, but showing a further modification of construction of the card-holder. Fig. 8 is a vertical cross-section thereof taken at the line $y y$. Fig. 9 is a view similar to Figs. 5 and 7, showing a still further modification of construction of the card-holder. Fig. 10 is a vertical cross-section thereof taken at the line $w w$. Fig. 11 is a detail perspective view of a portion of the card-holder, taken on the line $r r$ of Fig. 5. Fig. 12 is a similar view taken

on the line $s s$ of Fig. 7. Fig. 13 is a similar view taken on the line $t t$ of Fig. 9. Fig. 14 is a central longitudinal vertical section of a still further modification of the construction and arrangement of the card-holder. Fig. 15 is a vertical cross-section thereof taken at the line $v v$. Fig. 16 is a perspective view of one of the end pieces or catches of the card-holder, and Fig. 17 is a perspective view of the card-clamping bar detached.

Referring to Figs. 1, 2, 3, and 4, 1 designates a platen frame or carriage; 2, the platen; 3, the platen shaft or axle; 4, the paper-table; 5, an apron or deflector, and 6 a paper guide or finger. The platen-axle is mounted to turn in bearings 7 in the platen-carriage, and the platen is attached to said axle, so as to turn therewith, for convenience of rotation the platen-axle being provided at either end with a hand-wheel 8. The platen consists of a hollow core 9, preferably of wood, a rubber sheath or cover 10, and circular heads 11 and 12, fixed to the ends of the platen, the head 12 being provided with ratchet-teeth for coöperation with the line-space mechanism in the usual manner. The platen-axle passes through said heads and through the center of the core, and near each of said heads the said axle is flattened, as at 13, and provided thereat with a pin 14, which enters an obliquely-arranged slot 15 at the inner end of a leg or projection 16, extending substantially radially inward from a clamping-bar 17, which is disposed longitudinally of the platen for substantially its whole length and which is arranged parallel with the axis of the platen in a substantially radial slot 18, cut through the core and through the rubber sheath, as shown more clearly at Fig. 2. The uppermost edge of the bar 17 is bent at an angle to the body, so as to provide a small lip or flange 19 for holding the edge of the card upon the surface of the platen. Surrounding the platen shaft or axle is a coiled spring 20, which at one end bears against the head 11 and at the opposite end against a collar 21, fast on said axle, and the tension of said spring is such as to force the shaft toward the right and the pins thereon

to the upper ends of the oblique slots 15, and thereby cause the holding-bar 17 to be drawn in and held with the lip 19 down upon the surface of the platen. When the shaft or axle 5 is slid endwise toward the left, which may be done either by pushing upon the right-hand knob or wheel 8 or by pulling upon the left-hand knob, the pins 14 14 act upon the upper walls 22 of the slots and cam or push the bar 17 radially outward, and when the pressure or pull is released the spring 20 causes the shaft to slide in the opposite direction and the pins 14 14 to act upon the lower edges 23 of the slots and draw or wedge the bar down- 10 wardly or inwardly. The shaft is connected to the platen by a pin 24, which passes through a central slot 25 in the left-hand hub 26 of the platen and through a hole centrally of the shaft, the pin having a tight fit in said hole, 15 and by reason of this construction the shaft and platen are caused always to turn together, while at the same time the shaft may be slid endwise independently of the platen. When the shaft has been slid toward the left and the holding-bar 17 forced outwardly, the leading edge of the card or the like is passed under the lip or flange 19, which securely clamps the same under the tension of the spring 20 when the pressure upon the shaft is released 20 and the parts are restored to normal position. The platen may then be rotated until the desired portion of the card is brought to the printing point or plane, when the writing may then be begun. The platen may be rotated either by its shaft or axle or by the usual line-spacing devices. On the completion of the writing upon the card the shaft is pushed endwise again, so as to release the card from the holding-lip 19, which acts to 25 positively carry the card around with the platen. It will be understood, of course, that in conjunction with the platen may be used the usual pressure-roller and paper-guides for keeping the card close against the platen at or in the vicinity of the printing-point, so as 30 to obtain the best impressions, as common heretofore. At 27 are represented the heads of two small nails or screws, which are driven into the surface of the platen at the right-hand end thereof, and these or other suitable devices may be used as a guide for inserting the card, as will presently be explained. 35 28 denotes the head of another nail or screw, also driven into the platen at its right-hand end for the purpose of serving as a guide for the beginning of the printing, as will also presently be explained. I prefer to rotate the platen to the position shown at Fig. 3 when about to insert a card and to drop or push the 40 card substantially vertically into the space between the surface of the platen and the flange 19 and then after the card has been clamped to rotate the platen to the position shown at Fig. 4 and so that the flange 19 is 45 carried forward past the longitudinal vertical plane through the printing-point at which the types strike in order that the types shall not

come in contact with the said metallic flange 19. The devices 27 and 28 are provided for facilitating these operations. When the device 27 is brought around uppermost or to the position shown at Fig. 3, the operator is thereby informed that the clamp 19 (which at this time in practice is out of sight, assuming the operator to be seated at the front of the machine, as usual) is in proper position to receive the card if passed down in substantially a vertical direction, and hence the operator will be enabled to conveniently and properly insert or introduce the card at the most desirable or favorable place without the necessity for actually seeing the clamp, it being only necessary while the clamp is projected to pass the leading edge of the card down in contact with the rear side of the platen until such 55 edge abuts against the bar 17 and comes under the lip or flange thereof. When this has been done and the edge of the card has been clamped, the platen may be turned directly by rotation of the shaft until the device 28 is 60 uppermost or in the position shown at Fig. 4, at which time the operator will know that the clamp has been carried past the printing-plane and that it is safe to operate the types without danger of contact with the clamp, thus 65 rendering it unnecessary to lift the platen to ascertain this fact.

Referring to Figs. 5 and 6, the construction therein exhibited is the same in all respects as that hereinbefore described with reference 70 to Figs. 1 to 4, excepting that the clamping-bar instead of being provided with a lateral lip or flange is slotted lengthwise, as at 29, near its outer edge to receive the leading edge of the card, the bar 30, formed by said slot, serving as a flange to clamp or hold the card upon the platen under the tension of the spring 20, which is used in this construction at the left-hand end, as in the construction shown at Fig. 1. This clamping-bar being 75 made of very thin stock requires but a narrow slot in the platen to receive it and is located at a point where the types do not strike. Hence with this construction the card-holding platen may be used for regular 80 work on paper.

Referring now to Figs. 7 and 8, a construction like that shown at Figs. 5 and 6 is exhibited with the additional feature of an offset flange 31, formed out of the metal of the 85 bar 17 and provided as a stop to limit and determine the extent of introduction of the card into the slot 29.

Referring now to Figs. 9 and 10 in this construction, the bar 17, which is provided with 90 a lip 19, as in Fig. 1, is connected to the shaft or axle 3 at near each end by an obliquely-arranged link 32, pivoted to said bar and to said axle, and in place of a coiled spring surrounding the axle, as before, a coiled spring 95 33 is attached at one end to said bar and at the other end to said axle. When the axle is pressed toward the left, the links 32 cause the bar 17 to move outwardly, and when the pres-

sure is released the spring acts to return the bar, the card being inserted, as before, when the bar is projected.

Referring now to Figs. 14, 15, 16, and 17, the construction there shown is somewhat similar again to that illustrated at Fig. 1. In this modification the card-clamping devices proper are, however, differently constructed for the purpose of eliminating the clamping-bar, so that the platen may be used with paper for ordinary work. In this construction the rubber sheath or cover 10 need not extend for the entire length of the platen and the core or hollow wooden cylinder 9 is slotted or cut through substantially radially and at substantially diametrically opposite places, as indicated at 18^a and 18^b, and fitted into these slots or cuts at each end of the platen is a metallic device 34, consisting, essentially, of two parallel arms or members 35, a connecting-bar 36, and a hook 37. Each connecting bar or member 36 is provided with an oblique slot 38, which is engaged by the pin 14, projecting from the shaft or axle 3. 39 is a detachable clamping bar or plate formed at each end with a longitudinal slot 40 for the passage therethrough of the hooks 37 in the operations of attaching and detaching the bar. In order to attach the bar, the slot is aligned with the hooks 37 and passed down over the same until the bar rests upon the surface of the platen. Then the bar is pushed endwise toward the left and its left-hand end 41 is slid under the left-hand hook 37 and the right-hand end 42 is slid under the right-hand hook 37, thus locking the bar to the devices 34 and connecting it to the platen and its axle. When the axle is pressed leftward, as heretofore described, the two devices or frames 34 are projected and the bar 39 is lifted from the platen far enough to enable the edge of the card to be placed thereunder, and when the pressure is released the spring returns the parts and the card is clamped upon the platen. When it may be desired to use the platen without the card-holder, the bar 39 is detached by sliding it endwise off the platen toward the right until the hooks 37 and the slots 40 register, whereupon the bar or plate may be removed.

It will be observed that in each of the structures shown there is a connection between the clamping bar or plate and the shaft near each end of the bar, so that the bar is moved to equal extents at both ends and the same amount of pressure is exerted upon both ends of the bar to efficiently clamp the card in place.

While I prefer to use an elongated lip, flange, or bar extending for substantially the whole length of the platen and have shown this preferred form of construction in all of the views, it will nevertheless be understood that this device may be cut away at intervals, so as to provide only short lips, flanges, bars, or fingers, for in some cases they would serve the purposes satisfactorily; but the elongated

lip or flange is adapted for all sizes or lengths of card and besides gives a firmer grip or hold upon the card.

70

It will be understood, of course, that various other changes in detail construction and arrangement may be made without departing from the gist of the main feature of my invention.

75

What I claim as new, and desire to secure by Letters Patent, is—

1. In a type-writing machine, the combination of a platen, a platen shaft or axle which is movable in one direction independently of said platen and has a finger-wheel rigidly secured thereto, and a card-holder connected to said axle whereby the finger-wheel may operate through said axle to turn the platen so as to carry the card around the platen in either direction and whereby the said shaft may be moved independently of the platen to cause a movement of said card-holder relatively to the platen.

2. In a type-writing machine, the combination of a platen, a shaft or axle supporting the platen and having a limited endwise movement in its bearings, and a card-holder connected to said platen shaft or axle and adapted to hold the card upon the surface of the platen.

3. In a type-writing machine, the combination of a platen, a platen shaft or axle adapted to support and also to rotate with said platen and also move endwise thereof independently, and a card-holder connected to said platen shaft or axle and adapted to hold the card upon the surface of the platen.

4. In a type-writing machine, the combination of a platen, a platen-shaft or supporting-axle, and a substantially radially arranged card-holder adapted to be projected by an endwise movement of said shaft or axle and adapted to hold the card upon the surface of the platen.

110

5. In a type-writing machine, the combination of a platen having a substantially radial slot, a card-holder mounted to slide in said slot and adapted to hold the card upon the surface of the platen, and a shaft or axle adapted to support the platen and also to have a limited endwise movement in its bearings, and also adapted to move said card-holder.

6. In a type-writing machine, the combination of a revoluble platen, a card-holder constructed to rotate with the platen in either direction, a spring for drawing the card-holder inwardly toward the platen, and means operable at any point in the rotation of the platen for forcing the card-holder outwardly away from the platen against the tension of said spring.

120

7. In a type-writing machine, the combination of a revoluble platen, an inwardly spring-pressed card-holder constructed to rotate together with the platen in either direction, and means operable at any point in the rotation of the platen for projecting the card-holder outwardly against the tension of said spring.

130

8. In a type-writing machine, the combination of a revoluble platen, a card-holder constructed to rotate together with the platen in either direction, means operable at any point in the rotation of the platen for forcing the card-holder outwardly for the introduction of a card, and means for mechanically pressing the card-holder inwardly to hold the card. 70
9. In a type-writing machine, the combination of a revoluble platen, a card-holder constructed to rotate together with the platen in either direction, a cam operable at any point in the rotation of the platen for forcing the card-holder outwardly, and a spring operating through said cam for maintaining the card-holder in working position against the surface of the platen. 75
10. In a type-writing machine, the combination of a platen having a substantially radial slot, a card-holder adapted to slide therein and to hold the card upon the surface of the platen, and a shaft or axle supporting the platen and having a limited endwise movement in its bearings and connected to said card-holder and adapted to project it, and a spring adapted to restore said card-holder. 80
11. In a type-writing machine, the combination of a platen having a substantially radial slot, an endwise-movable shaft or axle, a card-holder adapted to move in said slot and having a pin and diagonal slot connection to said shaft or axle, whereby the movement of the card-holder is controlled by an endwise movement of the shaft or axle in its bearings. 85
12. In a type-writing machine, the combination of a platen having a substantially radial slot, a card-holder adapted to slide therein and to hold the card upon the surface of the platen, a shaft or axle adapted to support the platen and having a limited endwise movement and connected to said card-holder by pins and oblique slots, and a returning-spring. 90
13. In a type-writing machine, the combination of a platen having a substantially radial slot, a platen-supporting axle adapted to slide endwise for a limited distance and provided with pins, and a card-holder having inclined slots co-operating with said pins and adapted to hold the card upon the surface of the platen. 95
14. In a type-writing machine, the combination of a platen having a substantially radial slot, a platen-supporting shaft or axle adapted to be pushed endwise for a limited distance in one direction independently of said platen, a spring for returning said platen shaft or axle, and a card-holder mounted to slide in said slot in the platen and having an operative connection with said shaft or axle. 100
15. In a type-writing machine, the combination of a platen, a single integral card-holder thereon and extending for substantially the entire length thereof and provided with radial arms, and an endwise-movable rod or shaft connected to said card-holder through said arms, and constructed to project and retract the card-holder by opposite endwise movements. 105
16. In a type-writing machine, the combination of a platen, a card-holder arranged substantially in a radial position and adapted to hold the card upon the surface of the platen and an endwise-movable rod or shaft connected to said card-holder, and a returning-spring carried by the platen, for returning the rod or shaft to normal position. 110
17. In a type-writing machine, the combination of a platen having a substantially radial slot, a bar adapted to clamp the card upon the surface of the platen and having inwardly-projecting legs or portions provided with inclined slots, a longitudinally-movable platen-supporting shaft or axle provided with pins engaging said slot, and a returning-spring. 115
18. In a type-writing machine, the combination of a platen, a platen shaft or axle, a card-holder connected to the latter and provided with a detachable clamping bar or member so that the platen may be used for writing at will upon either short cards or longer sheets of paper. 120
19. In a type-writing machine, the combination of a platen, a platen shaft or axle movable longitudinally of the platen, frames or plates connected thereto so as to be moved substantially radially of the platen during the longitudinal movements of the shaft or axle, and a detachable clamping-bar carried by said frames or plates so that the platen may be used for writing at will upon either short cards or longer sheets of paper. 125
20. In a type-writing machine, the combination of a platen having substantially radial slots, plates or frames arranged to slide therein and provided with oblique slots and hooks, a platen shaft or axle provided with pins engaging said oblique slots, and a clamping-plate detachably connected to said hooks so that the platen may be used for writing at will upon either short cards or longer sheets of paper. 130
21. In a type-writing machine, the combination of hooks and a card-holder bar adapted to be engaged with and disengaged from said hooks by an endwise movement of said bar. 135
22. In a type-writing machine, the combination of a platen having hooks, and a bar or plate provided with slots or openings adapted to register with said hooks to enable its attachment to the platen by an endwise movement of said bar or plate and to enable its detachment from the platen after an endwise movement of the bar or plate in the opposite direction. 140
23. In a type-writing machine, the combination with a platen of a card-holder extending longitudinally thereof, a support for the card-holder, and means for producing a relative diagonal movement between the card- 145

holder and its support, whereby the card-holder may be moved or lifted from the peripheral surface of the platen.

24. In a type-writing machine, the combination with a platen of a single integral card-holder extending longitudinally thereof for substantially the entire length of the platen, a finger-piece movable longitudinally of the platen, and means controlled by the finger-piece for moving the card-holder to or away from the surface of the platen.

25. In a type-writing machine, the combination with a platen of a card-holder and a finger-piece provided with means for both rotating the platen and also moving the card-holder relatively to the platen, said platen and finger-piece being positively connected to rotate together.

26. In a type-writing machine, the combination with a platen of a card-holder, a spring for pressing the card-holder upon the platen, and a finger-piece provided with means for both rotating the platen and also lifting the card-holder from the platen, said platen and finger-piece being positively connected to rotate together.

27. In a type-writing machine, the combination with a platen and a card-holder, of a finger-piece movable in opposite rotative directions for rotating the platen and movable in still another direction for effecting a movement of the card-holder relatively to the platen.

28. In a type-writing machine, the combination with a platen and a card-holder of a finger-piece which may be turned to rotate the platen and which may also be moved longitudinally of the platen for effecting an independent movement of the card-holder.

29. In a type-writing machine, the combination with a platen and a card-holder of a finger-piece which may be turned to rotate the platen and which may also be moved longitudinally of the platen for effecting the movement of the card-holder relatively to the platen, and a spring, as 20, for restoring the finger-piece and card-holder to normal position.

30. In a type-writing machine, the combination of a platen, a plate, as 39, arranged thereon and extending beyond the printing-field thereof, a shaft for the platen which is movable independently thereof, and means arranged at both ends of the platen for connecting the shaft to both ends of the plate so that the plate may be lifted from the platen by a movement of the shaft.

31. In a type-writing machine, the combination of a platen, a plate, as 39, arranged thereon and extending beyond the printing-field thereof, a spring for pressing the plate upon the platen, and a shaft which is movable independently of the platen and is pro-

vided with means for pressing the plate away from the platen.

32. In a type-writing machine, the combination of a platen, a plate, as 39, arranged thereon and extending beyond the printing-field thereof, means for clamping said plate upon the platen, and means arranged at both ends of the plate for lifting it off the platen whereby the said plate may be moved to equal extents at both ends of the platen.

33. In a type-writing machine, the combination of a platen, a plate, as 39, arranged thereon and extending beyond the printing-field thereof and provided at its ends with means for pressing the plate 39 upon the platen to equal extents at both ends thereof, and a finger-piece provided with means at each end of the plate for lifting it off the platen.

34. In a type-writing machine, the combination of a platen, a detachable plate arranged thereon and extending beyond the printing-field thereof, a shaft for the platen, and means for enabling the plate to be lifted from the platen by a movement of the shaft.

35. In a type-writing machine, the combination of a platen, a plate arranged thereon and extending beyond the printing-field thereof, a spring for pressing the plate upon the platen, hand-operated means for pressing the plate away from the platen and means for detaching the said plate from the hand-operated means from the platen.

36. In a type-writing machine, the combination of a platen, a detachable plate arranged thereon and extending beyond the printing-field thereof, a spring for pressing the plate upon the platen, and a shaft which is movable independently of the platen and is provided with means for pressing the plate away from the platen.

37. In a type-writing machine, the combination of a platen, a detachable plate arranged thereon and extending beyond the printing-field thereof, means for clamping said plate upon the platen, hand-operated means connected to both ends of the plate for pressing it off the platen and means for detaching the said plate from its hand-operated means and from the platen.

38. In a type-writing machine, the combination of a platen, an endwise-movable platen-actuating axle, a card-holder connected to the axle, and means for mechanically pressing the card-holder against the platen or the card thereon.

Signed at the borough of Manhattan, in the city, county, and State of New York, this 2d day of April, A. D. 1898.

WALTER J. BARRON.
